CLAIM

I claim the ornamental design for an electronic device, as shown and described.

DESCRIPTION

FIG. 1 is a front perspective view of an electronic device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and

FIG. 9 is an enlarged view of the claimed portion of the electronic device shown in FIG. 1.

FIG. 10 is an enlarged view of the claimed portion of the electronic device shown in FIG. 2;

FIG. 11 is an enlarged view of the claimed portion of the electronic device shown in FIG. 3;

FIG. 12 is an enlarged view of the claimed portion of the electronic device shown in FIG. 5; and,

FIG. 13 is an enlarged view of the claimed portion of the electronic device shown in FIG. 8.

The evenly-dashed broken lines in the figures depict portions of the electronic device which form no part of the claimed design. The dot-dash broken lines represent a boundary of the claimed design and form no part thereof.

1 Claim, 13 Drawing Sheets
